ABSTRACT

A binding for a ski boot of the type having a pair of outwardly projecting pins at front portions of the sole thereof. The binding is primarily designed for cross-country skiing and includes a plate which is adapted to be secured to the top surface of a ski. A pair of upstanding retaining flanges extend upwardly from a front end of the plate, each of the upstanding flanges including a means to engage and retain an outwardly projecting pin on the sole of the boot. Means are provided on the retaining flanges for releasing the pins from engagement with the engaging and retaining means. A U-shaped bracket is fixed to a rear portion of the plate with the legs of the bracket extending upwardly from the ski to engage the sides of the boots retained by the binding. In one embodiment, at least one of the pins is spring loaded and the releasing means comprises a lever pivotably mounted to an upstanding flange, the lever having a camming portion adapted upon actuation to bear against the spring loaded pin to release the pin from engagement with the retaining flange. In another embodiment, the pins are fixed within the boots, a slot is provided in the retaining flanges for reception of the pins, and a spring biased latch retains the pins within the slot.

SKI BOOT BINDING

BACKGROUND OF THE INVENTION

1. Field of the Invention

This invention relates to a ski boot binding. In one of its aspects, the invention relates to a cross-country ski boot binding wherein the ski boot has outwardly projecting pins at a front portion thereof which are received and releasably retained by the binding.

2. State of the Prior Art

Cross-country ski boot bindings are a means of securing the boot to the cross-country ski. For cross-country purposes, the heel of the boot is permitted to move upwardly away from the ski whereas the toe of the boot is retained fixed against the ski so that the skier can raise his heel while skiing much the same way that one does while walking. One commonly used ski boot binding provides a pair of upstanding flanges for engagement with the sole of the ski boot. A pair of protuberances on the flanges fit over the sole of the ski boot to retain the sole therebeneath. A cable is secured tightly around the heel of the ski boot to force the boot into engagement with the retaining flanges of the binding. This so-called cable binding is effective in normal touring operation but the ski boot has a tendency to move laterally within the binding, which movement results in loss of "heel control" which is necessary for guiding the ski in downhill movement. In this type of binding, it is therefore difficult to negotiate more than simple turns while skiing downhill.

Another type of cross-country ski boot binding requires a special boot with a square extended sole at the front portion thereof. The binding comprises a toggle clamp which clamps onto the squared extended portion of the sole. This type of binding offers more heel control than the cable binding but requires a special type of boot which is adapted almost exclusively for cross-country skiing.

SUMMARY OF THE INVENTION

According to the invention, there is provided a cross-country ski boot binding wherein the soles of the shoes are provided with outwardly directed pins at a front portion thereof. The pins can be mounted in conventional hiking boots by a simple process, or the boots can be specially constructed with the pins. In any case, the boot can be of any shape and can be used as a hiking boot or any other type of boot.

The binding comprises a plate which is secured to the upper surface of a ski and a pair of upstanding retaining flanges at a front end of the plate. Each of the retaining flanges includes a means to engage and retain the outwardly projecting pins of the boot. At least one of the retaining flanges mounts a means for releasing the pins from engagement with the retaining flanges. Desirably, a U-shaped bracket is fixed to a rear portion of the plate with the legs of the U-shaped bracket extending upwardly to abut against the sides of a boot retained by the binding. The U-shaped bracket at the rear portion of the plate does not interfere with the normal operation of the boot and retains the boot in its predetermined orientation to give added heel control during downhill skiing.

In one embodiment, at least one of the pins in the boot is spring loaded and the retaining end engaging means comprises a lever pivotably mounted on one of the upstanding flanges, the lever having a camming sur-

face adapted to cam said pin out of engagement with the opening in the retaining flange.

In another embodiment, the retaining and engaging means comprises a slot in the upstanding retaining flanges and a latch, pivotably mounted to the retaining flanges, the latch hooking behind the pins to retain the pins in the slots. The latch is movable to a position for releasing the pins from the slot and means are provided to bias the latch in the retaining position with respect to the pins.

BRIEF DESCRIPTION OF THE DRAWINGS

The invention will now be described with reference to the accompanying drawings in which:

15 FIG. 1 is a plan view of a binding according to the invention;

FIG. 2 is a side elevational view in section taken along lines 2—2 of FIG. 1;

20 FIG. 3 is a front elevational view in section along lines 3—3 of FIG. 1;

FIG. 4 is a sectional view through lines 4—4 of FIG. 2;

25 FIG. 5 is an enlarged side elevational view of a release mechanism associated with the first embodiment;

FIG. 6 is an enlarged partial plan view of the release mechanism illustrated in FIG. 5;

FIG. 7 is a partial sectional view along lines 7—7 of FIG. 5;

30 FIG. 8 is a side view of a second embodiment of the invention; and

FIG. 9 is a plan view taken along lines 9—9 of FIG. 8.

35 DETAILED DESCRIPTION OF THE PREFERRED EMBODIMENTS

Referring now to the drawings, and to FIGS. 1—7 in particular, there is illustrated a ski 12 having a binding 14 secured to the top portion thereof through a plurality of screws 16. The binding 14 has a base portion 18 and upstanding retaining flanges 20 and 22 at a front portion thereof. A raised channel 24 is provided transversely of the binding at a rear portion thereof and retains a U-shaped bracket 26 whose legs extend upwardly from the ski to abut against the sides of the boot (shown in phantom lines in FIG. 1) retained by the binding. A gripping hole 28 is provided on the upstanding retaining flange 22 for reception of an outwardly directed pin 53 (FIG. 1) which may extend from the sole of the ski boot 46.

50 The upstanding flange 22 has a base 30 with a gripping hole 32 therein for reception of a spring biased pin 54 (FIG. 7). A release lever 34 is pivotably mounted on the upstanding retaining flange 20 by means of pivot pin 36. The front of the release lever 34 includes a camming portion 38 adapted to bear against and force retraction of the spring mounted pin 54. A tab 40 on the rear portion of the release lever 34 facilitates operation of the release mechanism. A spring 42 is secured at one end to the retaining flange 20 through a pin 44 and at the other end bears against the upper portion of the release lever 34 to bias the lever 34 into the inoperative position illustrated in FIG. 5.

55 Referring now specifically to FIG. 7, the shoe 46 has a sole 48 with a bore 50. A housing 52 in the sole 48 slidably retains a spring loaded pin 54 which is biased outwardly by spring 56. The pin 54 desirably is keyed

to the housing 52 so that it maintains a particular orientation with respect to the boot and with respect to the binding. As seen in FIG. 7, the outer surface of the pin 54 is beveled upwardly and outwardly. The upper surface of the camming portion 38 of release lever 34 is beveled correspondingly so that as the camming portion 38 bears against the outer end of the spring loaded pin 54, the pin is pushed into the housing 52, thereby releasing the pin from engagement with the hole 32 of the retaining flange 20.

The other pin 53 in the sole 48 can also be spring loaded although a spring loaded pin on the other side is unnecessary. Once the pin 54 is released from engagement with the upstanding flange 20, the pin 53 can be easily disengaged.

In operation of the embodiment illustrated in FIGS. 1 - 7, the boot is easily secured to the binding by inserting the pin 53 into hole 28 of the upstanding retaining flange 22. The other side of the boot is then brought down so that the outer end of the pin 54 bears against the top of the base portion 30 above the hole 32 of the retaining flange 20. Downward pressure on the boot will force the pin 54 into the housing 52 so that the pin 54 can move downwardly along the inner surface of base 30 until it reaches hole 32. At this point, the pin moves outwardly under the force of the spring 56 to engage the hole 32.

During normal skiing operation, the boot will be tightly retained in the binding with the heel being permitted to move upwardly with respect to the binding. As illustrated in FIG. 3, the retaining flanges 20 and 22 are slanted inwardly to retain the front of the boot against forward movement with respect thereto. During downhill skiing, the upstanding legs of the bracket 26 will restrain lateral movement of a central portion of the boot within the binding. Further, lateral movement of the boot within the binding is restricted by the positioning of the pins 53, 54 of the boot in the holes 28 and 32 of the retaining flanges 22 and 20 respectively. The boot is removed from the binding by simply pressing down on the tab 40 to cam the retractable pin 54 out of engagement with the hole 32 as described more fully above.

Reference is now made to FIGS. 8 and 9 for a description of the second embodiment of the invention. The ski 12 has a binding 60 secured thereto through a plurality of screws 70 in conventional fashion. The binding has a pair of identical front retaining flanges 62 extending upwardly from a base plate portion 68. Each of the retaining flanges has a retaining slot 64 and a hole 68. A spring member 72 is integrally formed with the base portion 68 and extends upwardly from a front portion thereof. A cradle 74 is formed at a top portion of the spring 72. Desirably, the base plate portion 68, the retaining flanges 62, and the spring 72 are all stamped from a single piece of material of, for example, a medium carbon steel. The material is of sufficient strength and resiliency such that the spring 72 provides a substantial upward pressure against the retainer 80.

A retainer 80 has a bight portion 82 positioned within the cradle 74 of spring 72. The retainer 80 is bent inwardly at 84 around the front portion of the retaining flanges 62 and fits through the holes 66 therein. The retainer 80 extends rearwardly at 86 along the inside edges of the retaining flanges 62 and is bent downwardly at 88 behind the pins 78 in a retaining position

illustrated in FIGS. 8 and 9. The inwardly bent portions 84 prevent forward and rearward movement of the retainer 80 with respect to the retaining flanges 62. The boot 46 has a sole 48 with a plate member 76 integrally molded therein or otherwise secured within the sole. A pair of pins 78 extend outwardly of the plate portion and outwardly of the sole to engage the retaining slots 64 of the flanges 62. The sole is cut away at 90 to provide a space for rearwardly directed portions 86 of the retainer 80.

The retainer 80 is movable between a retaining position illustrated in FIGS. 8 and 9 to a release position wherein the downwardly bent portions 88 move upwardly from behind the pins 78. The spring 72 acting through cradle 74 biases the bight portion 82 of the retainer upwardly with respect to the ski, thereby biasing the downwardly bent portions 88 into the retaining position illustrated in FIGS. 8 and 9. In order to release the downwardly bent portions 88 with respect to the pins 78, the bight portion 82 is pushed downwardly against the tension in spring 72, whereby the retainer pivots on the holes 66 in the retaining flanges 62 about portions 84 of the retainer 80. By this action, the bent portions 88 are raised with respect to the pins 78 so that the pins are released from engagement therewith. This latter position is the released position of the retainer 80. Although not illustrated in FIGS. 8 and 9, preferably, the bracket 26 is provided at a rear portion of the base plate 68 with a bracket 26 in the same fashion as illustrated in the first embodiment in the FIGS. 1 and 2.

The invention provides a simple means for securing a boot to a ski such that the boot is pivotably secured at a front portion to the ski, yet sufficient retaining means are provided in the connection and ancillary thereto by means of the bracket 26 to assure a positive heel control for the ski. The binding is easily secured to the ski boot and remains so secured during normal use. Yet, the boot is easily removed from the binding when it is desirable to do so.

Reasonable variation and modification are possible within the scope of the foregoing disclosure, the drawings, and appended claims without departing from the spirit of the invention.

The embodiments of the invention in which an exclusive property or privilege is claimed are defined as follows.

1. In combination with a boot, a ski, and a binding secured to the ski for mounting the boot on the ski so that the heel of the boot is freely vertically movable with respect to the ski in normal operation of the ski, the improvement comprising:

said boot having a sole with a pair of elongated pins mounted at a front portion thereof and projecting outwardly, at least one of the pins being retractably spring loaded in the sole;

the binding including a plate secured to the ski, the plate having a pair of upstanding flanges at a front portion thereof, the flanges being spaced and sized to snugly receive the front portion of the sole therebetween, each of the flanges including an opening to receive and retain the outwardly projecting pins on the sole of the boot; and

means movably mounted on the plate for releasing the spring loaded pin from engagement with the corresponding opening in the adjacent retaining flange, said releasing means including a cam lever

with a cam surface positioned to contact the outer end of the spring loaded pin, the cam surface being shaped to retract the spring loaded pin upon movement of the cam lever with respect to the plate.

2. The combination of claim 1 wherein the cam lever is pivotably mounted on the adjacent retaining flange and the cam surface is beveled with respect to the axis of the pin.

3. The combination of claim 2 wherein the cam lever is mounted for movement transverse with respect to the axis of the spring loaded pin.

4. The combination of claim 1 wherein the cam lever is mounted for movement transverse to the axis of the spring loaded pin.

5. The combination of claim 1 wherein the spring loaded pin has a beveled outer surface at an acute angle to the axis of the pin to facilitate retraction of the spring loaded pin while inserting the pin into the corresponding opening in the adjacent flange.

6. The combination of claim 1 and further comprising a U-shaped bracket secured to a rear portion of the plate, the bracket having upstanding legs near a central portion of the sole to restrain lateral movement of the boot with respect to the plate and yet permit free upward movement of the heel of the boot with respect to the ski.

7. In combination with a boot, a ski, and a binding secured to the ski for mounting the boot on the ski so that the heel of the boot is free to move vertically with respect to the ski in normal operation of the ski, the improvement which comprises:

said boot having a sole with a pair of elongated pins mounted at a front portion thereof and projecting outwardly therefrom;

said binding including a plate secured to said ski and a pair of upstanding flanges at a front portion of said plate, said flanges being spaced and sized to snugly receive the front portion of said sole therebetween, each of said flanges including a slot opening rearwardly of the flanges and sized to receive the elongated pins therein;

a retainer of generally U-shaped configuration extending forwardly of the boot, the intermediate portions of the legs of said retainer being pivotably mounted on the upstanding flanges of the plate, said retainer having portions extending rearwardly along sides of said flanges and the ends thereof bent downwardly behind said pins in said slots to retain said pins in said slots; and

means biasing said retainer into a latching position wherin the ends of the retainer are biased behind the pins, and wherein movement of the retainer in opposition to the biasing means moves the retainer ends from behind the pins so that the pins can be removed from the slots by rearward movement of the boot.

8. The combination of claim 7 wherein the rearwardly extending portions of said retainer are positioned on the insides of said flanges and the sole has portions thereof recessed to receive the rearwardly extending portions of the retainer.
